CORE BIT

Wiley B. Noble and John E. Hoffoss, Houston,
Tex., assignors to Reed Roller Bit Company,
Houston, Tex., a corporation of Texas

Application November 23, 1940, Serial No. 366,821

5 Claims. (Cl. 255—72)

This invention relates to core bits for use in taking samples of earth formation as a hole is being drilled. It has for its general object the provision of such a device which will be simpler and less expensive to manufacture and yet will have all of the desirable qualities of similar devices of the prior art.

Another object of this invention is to provide a core cutter assembly which will be extremely strong and rugged and which may be attached to or removed from the bit head in any field shop.

Other objects and advantages of this invention will become apparent from the following description taken in connection with the accompanying drawings wherein is set forth by way of illustration and example one embodiment of this invention.

In the drawings:

Fig. 1 shows a longitudinal cross section through a bit head constructed in accordance with this invention.

Fig. 2 is a transverse cross section taken along the line of 2—2 of Fig. 1.

Fig. 3 is a side elevation of one of the segments which carries one of the outside cutter bearings and forms a part of the structure shown in Fig. 1.

Fig. 4 is a top plan view of the structure shown in Fig. 3.

Fig. 5 is a fragmentary cross section along the longitudinal plane represented by the line 5—5 of Fig. 2.

Fig. 6 is a fragmentary side elevation showing the manner of joining together the segments of the cutter assembly and of joining this assembly to the body of the bit by welding.

Fig. 7 is an exploded view showing the various parts in longitudinal cross section but omitting the cutters.

Referring first to Fig. 1, the bit head 1 is threaded to the lower end of the outer barrel 2 and carries on its lower end the cutter assembly constructed in accordance with this invention. As shown, the device is depicted as drilling through a formation 3 and forming a core 4, which is passing upwardly into the inner core barrel 5. Carried within the bit head 1 and within the lower end of the inner core barrel 5 is a core catcher consisting of a catcher body 6 and pivoted dogs 7 adapted to dig into and break off the core when the bit is elevated with respect to the core. The bit head is provided with slush passageways 8 adapted to conduct slush from the annular space 9 between the inner and outer barrels down through the bit head and cause it to impinge upon the respective inner and outer cutters 10 and 11.

The cutter assembly, which carries the cutters 10 and 11, is composed of the cutters themselves, the inside cutter bearing ring 12, the outside cutter bearing segments 13, and the inside cutter

bearing supporting segments 14. The ring 12 is adapted to seat against a shoulder 15 formed in the lower end of the bit head but is not secured to that shoulder nor is it secured to the bit head in any way except through the segments 13 and 14, as will be presently described.

The ring 12 is provided at alternate points about its circumference with integral downwardly and outwardly extending bearing shafts 16 for the inside cutters 10 and with openings 17 adapted to receive the inner ends of the bearing shafts 16, which carry the outside cutters 11. The bearing shafts 16 extend downwardly and inwardly and are made integral with the segments 13. The segments 14 are provided with openings 18 for the reception of the outer ends of the bearing shafts 16. It will be appreciated that the number of the segments 14 will correspond to the number of the inside cutter bearing shafts 16 and that there will be a like number of the segments 13 alternating with the segments 14. The segments 13 and 14 together are of such an extent as to take up substantially the entire circumference of the completed structure.

In practice, the inside cutters 10 will first be assembled on the bearing shafts 16 and the segments 14 will be put in place on the outer ends of those shafts and secured thereto temporarily in some suitable manner as by tack welding. The outside cutters 11 will then be placed on the bearing shafts 16 of the respective segments 13 and these segments with the cutters thereon will be assembled with respect to the ring 12, so that the inside ends of the shafts 16 project into the holes 17 where they will likewise be secured temporarily as by tack welding. The entire cutter assembly thus provided is completed by joining the segments together along their edges by welding as shown at 20 and by welding the outer and inner ends of the shafts 16 and 18 respectively in the respective openings provided therefor, as shown at 21 and 22.

The cutter assembly thus provided may be mounted on the bit head 1 by merely placing it over the bit head and welding around the upper ends of the segments as shown at 23. This is all that is necessary to join this cutter assembly to the bit head. When the cutter assembly becomes worn or it becomes for any reason desirable to replace it, it can be removed merely by the use of a cutting torch to destroy the welded joint 23 and when this welded joint is destroyed the entire cutter assembly may be removed as a unit.

It will be seen from the foregoing, that means has been provided whereby all the objects and advantages sought by this invention may be achieved. It is further apparent that with the device described, it is possible to remove a cutter assembly from a bit head of a core bit, such as

that to which this invention relates, and to replace the same with a new assembly in the field by the use of no special tools other than the usual welding and cutting equipment to be found in the field. It will be appreciated that the cutters will not be disturbed in their relation to each other either during the removal of or during the attachment of the cutter assembly to the bit head. It is further apparent that no welding is necessary inside of the bit head or cutter assembly during the attachment or removal of the same and that no skill or precise measurements are required except for the usual welding skill and practice.

Having described our invention, we claim:

1. A core bit comprising a core barrel, a tubular bit head threadedly mounted on the lower end of said barrel, said bit head having portions on the inner and outer surfaces thereof at its lower end cut away to provide annular shoulders on said surfaces, a plurality of axially extending slush passageways in the bit head intermediate said inner and outer surfaces having discharge openings at the lower end of the bit head, an annular cutter assembly having spaced upwardly extending inner and outer annular members seated on said inner and outer shoulders respectively with said outer annular member detachably connected to said bit head by a weld, and roller cutters mounted between said inner and outer annular members and adapted to be positioned beneath the slush passageway discharge openings at the lower end of the bit head.

2. A core bit comprising a core barrel, a tubular bit head threadedly mounted on the lower end of said barrel, said bit head having portions on the inner and outer surfaces thereof at its lower end cut away to provide annular shoulders on said surfaces, a plurality of axially extending slush passageways in the bit head intermediate said inner and outer surfaces having discharge openings at the lower end of the bit head, an annular cutter assembly having spaced upwardly extending inner and outer annular members seated on said inner and outer shoulders respectively with said outer annular member detachably connected to said bit head by a weld, said inner annular member having a plurality of circumferentially spaced cutter shaft receiving openings, a cutter shaft carried by the inner annular member between adjacent openings and extending outwardly from the circumference of the inner annular member, said outer annular member comprising a plurality of welded segments, those of the segments facing the openings in the inner annular member having cutter shafts extending therefrom and entering said openings and those of said segments facing the shafts carried by the inner member having openings therein to receive the ends of the shafts carried by said inner members, and means connecting the free ends of said shafts in the openings into which they extend, and roller cutters on said shafts.

3. A core bit comprising a core barrel, a tubular bit head threadedly mounted on the lower end of said barrel, said bit head having portions on the inner and outer surfaces thereof at its lower end cut away to provide annular shoulders on said surfaces, a plurality of axially extending slush passageways in the bit head intermediate said inner and outer surfaces having discharge openings at the lower end of the bit head, an annular cutter assembly having spaced upwardly extending inner and outer annular members

seated on said inner and outer shoulders respectively with said outer annular member detachably connected to said bit head by a weld, said inner annular member having a plurality of circumferentially spaced cutter shaft receiving openings, a cutter shaft carried by the inner annular member between adjacent openings and extending outwardly from the circumference of the inner annular member, said outer annular member having a plurality of circumferentially spaced openings therein for receiving the outer ends of the cutter shafts extending outwardly from the inner member, and a cutter shaft carried by the outer annular member between adjacent openings therein and extending inwardly and entering the openings in the inner annular member, the ends of the shafts carried by one member being connected in the openings of the other member, and roller cutters on said shafts.

4. A core bit comprising a core barrel, a tubular bit head threadedly mounted on the lower end of said barrel, said bit head having portions on the inner and outer surfaces thereof at its lower end cut away to provide annular shoulders on said surfaces, a plurality of axially extending slush passageways in the bit head intermediate said inner and outer surfaces having discharge openings at the lower end of the bit head, an annular cutter assembly having spaced upwardly extending inner and outer annular members seated on said inner and outer shoulders respectively with said outer annular member detachably connected to said bit head by a weld, said inner annular member having a plurality of circumferentially spaced cutter shaft receiving openings, a cutter shaft carried by the inner annular member between adjacent openings and extending outwardly from the circumference of the inner annular member, said outer annular member having a plurality of circumferentially spaced openings therein for receiving the outer ends of the cutter shafts extending outwardly from the inner member, a cutter shaft carried by the outer annular member between adjacent openings therein and extending inwardly and entering the openings in the inner annular member, the ends of the shafts carried by one member being connected in the openings of the other member, welds connecting the ends of the shafts of one member to the openings in the other member, and roller cutters on said shafts.

5. A core bit comprising a core barrel, a tubular bit head threadedly mounted on the lower end of said barrel, said bit head having a portion on the inner surface thereof at its lower end cut away to provide an annular shoulder on said surface, a plurality of axially extending slush passageways in the bit head intermediate its inner and outer surfaces having discharge openings at the lower end of the bit head, an annular cutter assembly having spaced upwardly extending inner and outer annular members with the inner member seated on said inner shoulder and with the upper portion of the outer annular member of said cutter assembly connected to the lower outer portion of said bit head by a weld, and roller cutters mounted between said inner and outer annular members and adapted to be positioned beneath the slush passageway discharge openings at the lower end of the bit head, whereby said cutter assembly can be removed without disturbing said slush passageways.

WILEY B. NOBLE,
JOHN E. HOFFOSS.
